OF BALDWYN, MISSISSIPPI

GAME APPARATUS

Application filed December 29, 1930. Serial No. 505,411.

This invention relates to a game apparatus of that type including tracks upon which globular game pieces are rolled thereon for the purpose of scoring and the invention has for its object to provide, in a manner as hereinafter set forth, an apparatus of the class referred to which when employed will provide for the playing of a skillful, amusing and interesting game.

10 A further object of the invention is to provide, in a manner as hereinafter set forth and for the purpose referred to a game apparatus including means for automatically scoring a successfully played game piece.

15 A further object of the invention is to provide, in a manner as hereinafter set forth a game apparatus for the purpose referred to including means for automatically scoring a successfully played game piece and with 20 means for automatically returning such game pieces and unsuccessfully played game pieces to the front of the apparatus.

25 A further object of the invention is to provide, in a manner as hereinafter set forth and for the purpose referred to a game apparatus requiring dexterity on the part of a player to successfully roll a game piece to score.

30 A further object of the invention is to provide, in a manner as hereinafter set forth and for the purpose referred to a game apparatus including inclined tracks for rolling thereon game pieces and with the tracks so arranged as to offer resistance to and to assist the travel of the game pieces as they roll towards scoring points therefor.

35 A further object of the invention is to provide, in a manner as hereinafter set forth and for the purpose referred to a game apparatus including a guard to prevent the game pieces from being projected from off the apparatus when the player initially starts the game piece upon a track.

40 Further objects of the invention are to provide, in a manner as hereinafter set forth, a game apparatus for the purpose referred to which is comparatively simple in its construction and arrangement, strong, durable, 45 compact, amusing and interesting when used,

readily assembled and comparatively inexpensive to set up.

With the foregoing and other objects in view, the invention consists of the novel construction, combination and arrangement of 55 parts as hereinafter more specifically described, and illustrated in the accompanying drawings, wherein is shown an embodiment of the invention, but it is to be understood that changes, variations and modifications 60 can be resorted to which fall within the scope of the claims hereunto appended.

In the drawings wherein like reference characters denote corresponding parts 65 throughout the several views:—

Figure 1 is a top plan view of a game apparatus in accordance with this invention.

Figure 2 is a section on line 2—2, Figure 1.

Figure 3 is a section on line 3—3, Figure 1.

Figure 4 is a section on line 4—4, Figure 1. 70

Figure 5 is a section on line 5—5, Figure 1.

Figure 6 is a sectional elevation of the scoring device, broken away.

Figure 7 is a top plan view of the scoring device and with the casing therefor in 75 sectional plan.

Figure 8 is a front elevation of the casing for the scoring device.

Figures 9 and 10 are sectional details illustrating tracks in vertical sections. 80

The game apparatus includes a support generally indicated at 1 and including a rectangular forward part 20, a curved intermediate part 3 and a circular rear part 4. The diameter of the part 4 is materially 85 greater than the width of the parts 2 or 3. The support 1 can be constructed of any suitable material and of the desired width and length. The forward part 2 is arranged concentrically with respect to the rear part 4. 90 The support 1 is arranged at the desired height and is mounted upon and secured to spaced pairs of standards 5, 6 and 7 and a single standard 8 which is arranged between the pairs of standards 5, 6 and at the longitudinal median of the forward part 2. The support 1 upwardly inclines from its front to rear and the inclination thereof can be as desired.

At the transverse center of the part 4, it 100

is formed with a diametrically disposed row of spaced openings. The number of openings of the row as illustrated by way of example, is five, but this number can be increased or decreased if desired. Preferably five openings will be employed. The openings of the row are designated 9, 10, 11, 12 and 13. The diameter of each opening is such as to permit a globular player piece or ball 14 to pass therethrough. Preferably the number of player pieces or balls used is nine, but this number can be increased or diminished. The part 4 is also formed with an arcuate slot 15 which extends at a point in proximity to the front end of part 4 to a point in proximity to the axis of part 4 and is arranged adjacent one side of the longitudinal median of support 1.

Secured to the rear portion of each side of the part 2, throughout the sides of part 3 and throughout the edge of part 4 is a vertically disposed reticulated guard 16. The guard 16 is of the desired height and prevents the player pieces from being projected off the apparatus when the player pieces are rolled in a direction towards the openings in the part 4.

The support 1 has arranged thereon means to provide a roll-off surface 17. The said means consists of transversely extending spaced bars 18, 19 secured upon the forward portion of the forward part 2 of the support 1. Positioned upon as well as being secured to the bars 18, 19 is a rectangular plate 20 of a width corresponding to the width of the part 2 of the support 1. The upper face of the plate 20 provides the rolling off surface for the player pieces or balls 15. The plate 20 is of a length greater than half the length of the part 2 of support 1 and the forward end of plate 20 is flush with the forward end of the support 1.

Secured upon the upper face of the support 1 is a series of spaced parallel, continuous, upstanding strips, each standing on its lower lengthwise edge thereof. The strips provide track members 21, 22, 23, 24, 25, 26, 27, 28, 29, 30, 31, 32, 33 and 34. Each of said members with the exception of member 21 includes a horizontal part 35, an arcuate part 36 and a curved part 37 greater than a half circle. The track member 21 includes a horizontal part 35', an arcuate part 36' and a circular part 37'. The parts 37 are concentrically arranged relatively to each other and to part 37'. The members 21, 34 are the outer members of the series and are positioned adjacent the side edges of parts 2, 3 and the part 4 of support 1. The front ends of the track members abut the rear end of plate 20 and are flush with the rolling off surface 17. The curved parts 37 progressively increase in diameter from the circular part of member 21 to the part 37 of member 34. The arcuate parts of said members gradually decrease

in length from the arcuate part of member 21 to the arcuate part of member 34. The arcuate part 36' of member 21 registers with one side edge of the slot 14 from end to end of such edge. The rear ends of the members 22 to 33, both inclusive, register with the other side edge of the slot 14. The end of member 34 abuts the arcuate part 36' of member 21 and extends across slot 14.

Depending from the end of the support 1 is a hanger plate 38 which has secured to the front portion of its lower face a collecting trough 39. Secured to the lower face of the part 4 of support 1 and disposed diametrically thereof, as well as positioned below the openings 9 to 13 is a combined collector and deflector member for successfully played player pieces or balls. The combined collecting and deflecting member is indicated at 40. Leading rearwardly from the center of the member 40 and inclining downwardly towards its rear end is a conducting chute 41 for the successfully played balls or player pieces 15. Arranged below the part 4 of support 1, as well as being secured to said part is a receiver member 42 for unsuccessfully played player pieces or balls 15. The member 42 aligns with the slot 14 and the latter opens into the upper end of the member. The forward end of member 42 is open and leading therefrom to the front of the apparatus is an inclined conducting chute 43 for unsuccessfully played balls. The chute 43 discharges into the collecting trough 39. Arranged below the support 1 and extending from a point below the rear end of the chute 41 to and opening into the collecting trough 39 is a return chute or runway 44 for successfully played player pieces or balls 15. The rear end of the chute 44 is enlarged as at 45 for the purpose of receiving the successfully played player pieces or balls 15 and the manner in which the successfully played balls are discharged into the rear end 45 of the chute or runway 44 will be presently referred to.

The track forming members are of like height and each is of the same height throughout. Each pair of opposed track members are associated to provide a track. The track members are disposed at the same inclination as the inclination of the support 1. The top edge of each track member is oppositely beveled as at 46, 47, Figure 9. The beveled edge portion 46 of one track member coacts with the beveled edge portion 47 of another track member to provide a track for the player piece or ball 15 to roll over when it is being played.

The top edges of the track members 21, 28, 29 and 34 are beveled from end to end, but the top edge of each of the other track members at one side thereof is formed with a vertically disposed concave groove. The concave grooves of the members 22 and 23 associate with each other. The concave grooves of the members 24 and 25 associate with each

other. The concave grooves of the members 26 and 27 associate with each other. The concave grooves of the members 30 and 31 associate with each other and the concave 5 grooves of members 32 and 33 associate with each other. Each pair of associated concave grooves register with an opening formed in the part 4 of support 1 and the associated concave grooves reduce the thickness of the 10 pair of opposed track members so that when a ball reaches a pair of associated concave grooves it passes down through the same and through the openings with which the pair of concave grooves is associated. The grooves 15 of each pair of associated grooves are indicated at 48, 49, Figure 10. Each grooved track member has its top edge beveled from one side of the groove therein to one end of the member and from the other side of the 20 groove therein to the other end of the member.

The apparatus includes an automatically movable co-operable scoring device comprising a casing including front and rear walls 25 50, 51 respectively, a pair of side walls 52, 53, a bottom 54 and a top 55. The casing is arranged centrally with respect to the part 4 at the rear of the latter, suitably coupled therewith, is of greater height than part 4 30 and has its front wall provided with an inverted triangular shaped sight opening 56. Secured to the inner faces of the front walls 50, 51 centrally thereof are studs 57 and 58 respectively. Extending through the walls 35 50, 51 and studs 57, 58 is a stationary shaft 59 which is fixedly secured in position to the studs by a pin 60. Revolvably mounted on the shaft 59 is a score indicator consisting of a ratchet wheel 61 provided with spaced score 40 indicators 62. The indicators aggregate progressively in multiples of five and as illustrated by way of example, the indications consist of nought, five, ten, fifteen, twenty, twenty-five, thirty, thirty-five, forty and forty-five. 45 The aggregate score indicators as shown are employed when a player uses nine balls to play the game. It is to be understood that the indicators can be as desired and that any desired number of player pieces or balls 15 50 can be used for playing the game. Fixed to the shaft 59 is a pair of collars 63 to prevent shifting of disc 61 relative to shaft 59. Interposed between the hub 64 of the disc 61 and the collars 63 are a pair of ratchet disc 55 operating levers 65 which are loosely mounted on shaft 59. One end of the levers 65 are connected together by cross pieces 66 and to which is attached a vertically extending controlling spring 67, the latter having its lower 60 end anchored as at 68 to the bottom 54. The teeth of the ratchet 61 are indicated at 69 and coacting therewith is a spring controlled latch 70 to arrest anticlockwise movement of the disc 61. The spring controlled latch 70 65 is carried by a cross piece 71 which is secured

to the studs 57, 58 and arranged below the disc 61.

The other end of the levers 65 has positioned therebetween the upper end 72 of a shifting rod 73 for said levers 65. The upper 70 end 72 of rod 73 is pivotally connected to the levers 65 by a pivot member 74.

An operating lever is employed for shifting or pulling the rod 73 for the purpose of operating levers 65 to shift the disc 61 and such 75 operating lever is indicated at 75. The rear end of the lever 75 has a loose pivotal connection as at 76 with the rear wall 51 of the casing and such connection is arranged in proximity to the side wall 53 of the casing. 80 The lever 75 projects towards the front of the apparatus and extends through an opening 77 formed in the front wall 50 of the casing. The front end of the lever 75 is provided with a cup 78 to receive a successfully played 85 player piece or ball 15 and the weight thereof will lower the lever 75, carrying the rod 73 therewith and providing for a spring pressed latch 79 carried by the levers 65 to engage a tooth 69 of the disc 61 to shift the 90 latter the length of a tooth. The rod 73 and lever 75 are provided with openings 80 for adjustably connecting them together. The cup or receiver 78 carried by the front end of lever 75 is positioned below the rear end of 95 the successfully played ball conducting chute 41. The lever 75 is held in upward position by the controlling spring 67 acting through the levers 65 and rod 73 upon lever 75. When a successfully played ball is discharged from 100 chute 41 into the cup or receiver 78 the lever 75 is lowered and lowering movement is continued until the player piece carried by the cup 78 is discharged into the end 45 of the chute 44 and the latter conducts the ball or 105 player piece to the collecting trough 39. When the lever 75 is freed by the weight of the ball or player piece the spring 67 acts to restore the lever 75 to the position shown in Figure 2. 110

A means is employed for resetting the scoring device, that is to say for shifting the disc 61 until the indication nought appears to the sight opening 56. Said means consists of a pull cord 81 which is attached as at 82 to the lever 75 and then passes under a sheave or pulley 82 and then passes to the front of the apparatus and has its front end connected as at 83 to a pivoted shifting lever 84 therefor. The lever 84 is oscillated to provide 115 for an intermittent rotation of the disc 60 to bring the indication nought to the sight opening 56. This action is the resetting or restoring device to its initial or normal position. 120

The inclinations of the tracks tends to retard the travel of the player pieces and also tends to assist the travel of the player pieces towards the openings formed in the part 4 of the support 1. That is to say the inclination 130

of the tracks will retard somewhat the rolling action of the balls towards the openings 12 and 13 but after passing such openings and traveling to the left of the part 4 the inclination of the tracks will be such as to assist the balls in rolling towards the openings 9, 10 and 11.

It will be assumed that a player has rolled the ball on the track provided by the track members 25, 26 and as the ball travels over such track and reaches the rear end thereof it will be discharged through the slot 14 into member 42. It will be assumed that the player has rolled the ball over the track provided by the track members 24, 25 and that the ball has such speed as it passes beyond the opening 12 and it will run around the part 4 and be discharged into the slot 14. It will also be assumed that the player has rolled the ball upon the track provided by the track members 24, 25 and that the speed of the ball is such that when it reaches the opposed concave grooves of such members 24, 25 it will drop and pass through the opening 12 into the member 40 and be directed to the chute 41, travel through chute 41 and drop onto the cup 78 lowering lever 75 and thereby automatically operate the scoring device.

The player rolls the ball from the rolling off surface 17 and it requires considerable skill to have the ball leave the rolling off space 17 upon a track which has arranged intermediate its ends an opening for the passage of a successfully played ball.

The casing has attached to the top wall 55 thereof an illuminating element 85 employed for lighting the casing when occasion requires so that the aggregated score made by the player will be readily visible through the sight opening 56.

What I claim is:

1. In a game apparatus a support including a rectangular part terminating in a circular part, the latter being formed with a diametrically disposed row of spaced openings and a curved slot arranged substantially radially thereof, said slot having one end in proximity to the axis and its other end in proximity to the outer edge of said circular part, an elevated ball rolling off surface positioned upon a portion of said rectangular part, a series of parallel, elongated, spaced, upstanding continuous strips standing on the lower lengthwise edges and being arranged to provide parallel tracks positioned above said support for the travel of rolling bodies, said strips having one end thereof abutting one end edge of the playing surface, said strips with the exception of a pair thereof having their other ends flush with one side wall of said slot for the discharge of rolling bodies into the latter, one of the strips of said pair having its other end arranged at the inner end of said slot and a stretch thereof flush with the other side wall of the slot, the

other strip of the pair having a stretch thereof flush with the outer end wall of the slot and its other end abutting that strip flush with a side wall of the slot, said openings arranged between certain of said strips below the tracks formed by the latter, and said strips providing the tracks arranged above the openings having means for the passage of rolling bodies from off the tracks, down between such strips and through said openings.

2. In a game apparatus, a support having a circular part and a rectangular part merging into the former, the diameter of the circular being greater than that of the rectangular part, an elevated playing piece rolling off surface mounted upon a portion of said rectangular part, said circular part being formed with a diametrically disposed row of spaced openings and a substantially radially disposed slightly curved rectangular slot, continuous upstanding spaced elongated parallel strips standing on their lower lengthwise edges and providing elevated tracks for rolling bodies, said tracks extending from the forward edge of said surface to said slot and each formed of a horizontal stretch merging into a circular stretch, one of said strips having a stretch thereof flush with one side wall of the slot, another of said strips having a stretch flush with the outer end wall of the slot and abutting the said other strip, certain of said tracks arranged over said openings, and the strips forming the said certain of said tracks provided with means for the passage of rolling bodies from off of said tracks, down between such strips and through said openings.

3. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, and the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough.

4. A game apparatus including a series of parallel, elongated, spaced, upstanding continuous strips standing on the lower lengthwise edges thereof and having the upper portion of the opposed faces thereof beveled to

provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, and the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, all of the said tracks being disposed at an inclination thereof from the front end to the rear end thereof.

5. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefore, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, and the other of said tracks having curved rear parts greater than a half circle, arranged concentrically to each other and to said circular part.

6. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefore, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks

through said openings, the other tracks of said series having the width thereof throughout less than the diameter of the rolling bodies to prevent the latter passing downwardly therethrough, all of the said tracks being disposed at an inclination thereof from the front end to the rear end thereof, one of said tracks having a circular rear part, and the other of said tracks having curved rear parts greater than a half circle, arranged concentrically to each other and to said circular part.

7. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefore, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, and each of said tracks having an arcuate intermediate part merging into said rear part and a horizontal part merging into said arcuate part.

8. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefore, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, all of the said tracks

being disposed at an inclination thereof from the front and to the rear end thereof, one of said tracks having a circular rear part, the other of said tracks having curved rear parts 5 greater than a half circle, arranged concentrically to each other and to said circular part, and each of said tracks having an arcuate intermediate part merging into said rear part and a horizontal part merging into said arcuate 10 part.

9. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, 15 the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, and said support 20 formed with a slot common to the rear ends 25 of said tracks for the passage therethrough of unsuccessfully played rolling bodies.

10. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced 40 openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly 45 from said several tracks through said openings, the other tracks of said series having the width thereof throughout less than the diameter of the rolling bodies to prevent the latter passing downwardly therethrough, 50 one of said tracks having a circular rear part, the other of said tracks having curved rear parts greater than a half circle, arranged concentrically to each other and to said circular part, and said support formed with a slot common to the rear ends 55 of said tracks for the passage therethrough of unsuccessfully played rolling bodies.

the passage therethrough of unsuccessfully played rolling bodies.

11. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, each of said tracks having an arcuate intermediate part merging into said rear part and a horizontal part merging into said arcuate part, and said support formed with a slot common to the rear ends of said tracks for the passage therethrough of unsuccessfully played rolling bodies.

12. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, said support formed with a slot common to the rear ends of said tracks for the passage therethrough of unsuccessfully played rolling bodies, the said rolling bodies passing through said openings being successfully played, and means carried by said sup-

port for conducting the successfully played rolling bodies to operate a scoring device.

13. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, said support formed with a slot common to the rear ends of said tracks for the passage therethrough of unsuccessfully played rolling bodies, the said rolling bodies passing through said openings being successfully played, and means carried by said support for conducting the successfully played rolling bodies to operate a scoring device.

14. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, each of said tracks having an

arcuate intermediate part merging into said rear part and a horizontal part merging into said arcuate part, said support formed with a slot common to the rear ends of said tracks for the passage therethrough of unsuccessfully played rolling bodies, the said rolling bodies passing through said openings being successfully played, and means carried by said support for conducting the successfully played rolling bodies to operate a scoring device.

15. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, said support formed with a slot common to the rear ends of said tracks for the passage therethrough of unsuccessfully played rolling bodies, the said rolling bodies passing through said openings being successfully played, means carried by said support for conducting the successfully played rolling bodies to operate a scoring device, and means for conducting the unsuccessfully played and successfully played rolling bodies to the front of said support.

16. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width there-

of throughout less than the diameter of the rolling bodies to prevent the latter passing downwardly therethrough, one of said tracks having a circular rear part, the other of said tracks having curved rear parts greater than a half circle, arranged concentrically to each other and to said circular part, said support formed with a slot common to the rear ends of said tracks for the passage therethrough 5 of unsuccessfully played rolling bodies, the said rolling bodies passing through said openings being successfully played, means carried by said support for conducting the successfully played rolling bodies to operate a 10 scoring device, and means for conducting the unsuccessfully played and successfully played rolling bodies to the front of said support.

17. A game apparatus including a series 20 of parallel, elongated, spaced, upstanding, continuous strips standing on the lower lengthwise edges thereof and having the upper portion of the opposed faces thereof beveled to provide a series of parallel tracks 25 for the travel thereon of rolling bodies, a support therefor, said support having spaced openings positioned below several of said tracks, the width of the major portion of the said several tracks being less than the diameter 30 of said rolling bodies to prevent said bodies passing downwardly thereof, the strips forming the said several tracks provided intermediate the ends of the opposed faces thereof with oppositely disposed opposed up- 35 standing coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each 40 other and to said circular part, each of said tracks having an arcuate intermediate part merging into said rear part and a horizontal part merging into said arcuate part, said support formed with a slot common to the rear 45 ends of said tracks for the passage therethrough of unsuccessfully played rolling bodies, the said rolling bodies passing through said openings being successfully played, means carried by said support for 50 conducting the successfully played rolling bodies to operate a scoring device, and means for conducting the unsuccessfully played and successfully played rolling bodies to the front of said support.

18. A game apparatus including a series 60 of parallel, elongated, spaced, upstanding continuous strips standing on the lower lengthwise edges thereof and having the upper portion of the opposed faces thereof beveled to provide a series of parallel tracks

for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, said support formed with a slot common to the rear ends of said tracks for the passage therethrough of unsuccessfully played rolling bodies, the said rolling bodies passing through said openings being successfully played, means carried by said support for conducting the successfully played rolling bodies to operate a scoring device, means for conducting the unsuccessfully played and successfully played rolling bodies to the front of said support, and a vertically disposed guard secured to the side and rear edges of said support adjacent the outer of said tracks. 95

19. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, said support formed with a slot common to the rear ends of said tracks for the passage therethrough of unsuccessfully played rolling bodies, the said rolling bodies passing through said openings being successfully played, means carried by said support for conducting the successfully played rolling bodies to operate a scoring device, means for conducting

the unsuccessfully played and successfully played rolling bodies to the front of said support, and a vertically disposed guard secured to the side and rear edges of said support adjacent the outer of said tracks.

20. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, one of said tracks having a circular rear part, the other of said tracks having curved rear parts greater than a half circle, arranged concentrically to each other and to said circular part, each of said tracks having an arcuate intermediate part merging into said rear part and a horizontal part merging into said arcuate part, said support formed with a slot common to the rear ends of said tracks for the passage therethrough of unsuccessfully played rolling bodies, the said rolling bodies passing through said openings being successfully played, means carried by said support for conducting the successfully played rolling bodies to operate a scoring device, means for conducting the unsuccessfully played and successfully played rolling bodies to the front of said support, and a vertically disposed guard secured to the side and rear edges of said support adjacent the outer of said tracks.

21. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, and the strips forming the said several tracks provided intermediate the ends of the opposed faces thereof with oppositely disposed op-

posed upstanding coacting means for the passage of the rolling bodies downwardly from said several tracks through said openings, the other tracks of said series having the width thereof throughout less than the diameter of the rolling bodies to prevent the latter passing downwardly therethrough, the beveled portions of the opposed faces of the strips providing for the rolling bodies to partly depend between the strips when traveling over the tracks.

22. A game apparatus including a series of parallel, elongated, spaced, upstanding continuous strips standing on the lower lengthwise edges thereof and having the upper portion of the opposed faces thereof beveled to provide a series of parallel tracks for the travel thereon of rolling bodies, a support therefor, said support having spaced openings positioned below several of said tracks, the width of the major portion of the said several tracks being less than the diameter of said rolling bodies to prevent said bodies passing downwardly thereof, the strips forming the said several tracks provided intermediate the ends of the opposed faces thereof with oppositely disposed opposed upstanding coacting means for the passage of the rolling bodies downwardly from said several tracks through said openings, the other tracks of said series having the width thereof throughout less than the diameter of the rolling bodies to prevent the latter passing downwardly therethrough, the beveled portions of the opposed faces of the strips providing for the rolling bodies to partly depend between the strips when traveling over the tracks, said support formed with a slot common to the rear ends of said tracks for the passage of unsuccessfully played rolling bodies, said openings providing for the passage of successfully played balls, means carried by the support for conducting the successfully played balls to operate a scoring device, and means operated from the front of the support for returning the scoring device to normal position.

In testimony whereof, I affix my signature hereto.
